UNITED STATES PATENT OFFICE.

CLIFFORD H. GREEN, OF GRAND RAPIDS, MICHIGAN, ASSIGNOR TO NATIONAL PIANO MANUFACTURING COMPANY, OF GRAND RAPIDS, MICHIGAN, A CORPORATION OF ILLINOIS.

SPEED-EQUALIZING DEVICE FOR PHONOGRAFES, &c.

1,387,704.

Specification of Letters Patent. Patented Aug. 16, 1921.

Application filed June 14, 1918. Serial No. 239,981.

To all whom it may concern:

Be it known that I, CLIFFORD H. GREEN, a citizen of the United States, residing at Grand Rapids, in the county of Kent and State of Michigan, have invented new and useful Improvements in Speed-Equalizing Devices for Phonographs, &c., of which the following is a full, clear, and exact description.

10 My invention relates to actuating mechanism for revolving mechanical devices, and particularly the actuating mechanism for the records of phonographs and graphophones.

15 The electric motors now in extensive use for winding the springs in the mechanism for revolving the records of phonographs must be started whenever the spring needs winding and stopped whenever the spring 20 is sufficiently rewound. These motors are affected by the variations in the voltage of the electric current used to operate them. The greater the voltage the greater the speed. The pitch of the sound reproduced 25 from the records in the phonograph varies with the speed, so it will be apparent that in order to obtain an absolutely correct reproduction of sound, the effect resulting, primarily, from the variations of the voltage 30 must be overcome.

The objects of my invention are to render the starting and stopping of the electric motor unnecessary, in view of the fact that the motor can run all the time, and to maintain the rotation of the record bearing member at a given predetermined speed which will not be affected by the variations of the speed of the motor. I accomplish these results by the means hereinafter fully described; and as particularly pointed out in 40 the claims.

In the drawings:

Figure 1 is a side view of a motor driven actuating mechanism for the records of phonographs attached to the underside of a fragment of the record supporting platform showing my improvements applied thereto.

Fig. 2 is a horizontal view thereof taken on dotted line 2-2, Fig. 1, looking in the 50 direction indicated by the arrows.

Figs. 3, 4 and 5 are detail views illustrating the construction of the device for transmitting the motion derived from the elec-

tric motor to the shaft that rotates the turntable upon which the record is mounted.

Referring to the drawings, A represents the platform or top of a phonograph consisting usually of a square board; B the turntable, which is suitably mounted on the upper end of a vertical shaft C journaled in the center of said platform and 6 the metal frame work which is secured to and depends from the underside of the platform in which the actuating mechanism for the turntable is assembled.

Shaft C extends down through the top plate of frame work 6 and has the heel thereof journaled in suitable bearings in the lower plate of said frame work. Just above its lower bearings shaft C has a comparatively large gear 7 securely mounted thereon which meshes with a barrel-pinion 8 on the lower end of a vertical shaft 9 which latter is, preferably, likewise journaled in the top and bottom plates of frame work 6. 70 Near its upper end this last mentioned shaft 9 has a worm-gear 10 securely mounted thereon which meshes with and drives a worm 12 on a horizontal shaft 13 that is journaled in upright members arising from the bottom plate of said framework 6. Between its bearings shaft 13, is provided with any suitable kind of a centrifugal governor 14, substantially as shown in the drawings, and this governor includes a disk 26 securely mounted on one end of shaft 13 which is engaged by a brake (not shown). The centrifugal governor and the brake mechanism, just mentioned, while necessary, do not form any part of my invention, and it 80 is, therefore, deemed unnecessary to describe the same in detail.

About midway between gear 7 and the upper plate of framework 6 shaft C has a large gear 16 loosely mounted thereon and 95 held in place by a collar 16^a securely fastened to said shaft, and this gear is engaged by a worm 17 mounted upon a horizontal shaft 27, that is journaled in suitable standards made integral with framework 6. One 100 end of shaft 27 extends through its bearings and has a sheave 18 thereon through the medium of which and a belt 19 said shaft 27 is driven by an electric motor X. Motor X is constructed in accordance with 105 any of the small electric motors now on the

market, and is fastened to and suspended from the underside of platform A, and instead of driving shaft 27 through the medium of a belt and sheave it may be geared 5 to said shaft, or, for that matter, said shaft 27 may be extended and constituted the armature shaft of a motor.

Gear 16 is connected to and supports a circular casing 20 above it by means of corresponding 10 spacing bolts 21, 21, and this casing is concentric to and loose on shaft C. The upper portion of casing is more or less of an inverted cup-shape, except that its circular edges are flanged outward, and the mouth thereof closed by means of a circular 15 plate 22, the margins of which are secured to the annular edges of the casing by means of screws or bolts. The inner circumference of the cylindrical side of the casing has an annular leather facing 23 tightly fitted 20 therein and secured thereto by cement or other suitable means. Inclosed within this leather facing is a spiral expansion spring 24 which is made of flat steel and has its inner 25 end bent in toward the center of shaft C and permanently secured thereto by entering a transaxial slot 25 therein. This spring is of such size that when it is at a stated predetermined minimum tension—that is 30 when it has expanded to a certain extent, its outer convolution will frictionally engage the leather facing 23 and derive motion therefrom and immediately impart any motion acquired by said casing to shaft C, 35 when the casing travels at a predetermined certain speed. When the casing revolves at a greater speed than said predetermined speed greater friction will be generated between its inner circumference and the outer 40 convolution of the spring, and said outer convolution will wind slightly and thus contract the diameter of the perimeter of the spring. The casing will then slip and move faster than the spring and cease to impart motion to the same and shaft C during 45 momentary short intervals, thus, catching hold of and imparting a forward motion to and then releasing the spring, but not to the extent of winding the spring so that it can of 50 itself and unaided by said continuously revolving motor drive-shaft C, but only to the extent of imparting sufficient portion of the motion to the casing to said shaft C to cause the latter to revolve at the predetermined 55 speed it is desired to impart to the record bearing member.

In operation, electric motor X imparts motion to shaft 27, which, through the medium of worm 17 revolves gear 16. As hereinbefore stated, gear 16 is connected to and imparts its motion to the casing, and the latter through the medium of the leather facing in its interior imparts a motion to and winds up spring 24 by reason of the 65 frictional engagement between the same and

the outer convolution of the spring until said spring has been wound up and the diameter of the outer convolution thereof is decreased in diameter to such an extent that its frictional contact with the said facing 70 will no longer be sufficient to wind the spring, whereupon the convolution of the casing will no longer impart its motion to the spring. The latter, therefore, when at its certain minimum tension, will receive 75 motion from the casing and when at a certain maximum tension it will cease to take motion therefrom. It will thus be evident that the motor may run all the time, and that the spring as it automatically unwinds will 80 impart motion to shaft C at a certain normal speed that will not vary, thus insuring the rotation of shaft C, the turntable mounted thereon and the record mounted upon said shaft at a reliable and equable speed, 85 which will not vary the pitch of sound reproduced by the record and will result in a correct reproduction of the instrumental or vocal matter of the record.

It is possible to use my improvements 90 without the use of the governor, but I prefer to use it in connection therewith, because it regulates the speed and the governor prevents any variation in that speed, as for, instance, at the moment when the spring 95 ceases to be wound by the leather facing and when said spring again commences to receive motion therefrom.

What I claim as new is:—

1. In speed equalizing devices for phonographs, the combination with a revoluble driven member, and a revoluble driving member, of a contrivance consisting of two parts the peripheries of which are frictionally engageable, one of which is permanently connected to the driven member and the other to the driving member, to the former of which motion is imparted through the medium of said parts, while the driving member is revolving below a predetermined speed.

2. In speed equalizing devices for phonographs, the combination with a revoluble driven member, and a revoluble driving member, of a contrivance consisting of two 115 concentrically arranged parts, the peripheries of which are frictionally engageable, one of which is permanently connected to the driven member and the other to the driving member, to the former of which motion is imparted through the medium of said parts, while the driving member is revolving below a predetermined speed.

3. In speed equalizing devices for phonographs, the combination with a revoluble 125 driven member and a revoluble driving member, of a contrivance consisting of two parts, one of which is expansible and is permanently connected to the driven member and the other of which surrounds said ex- 130

pansible part and is connected to said driving member and imparts motion to the driven member only at a predetermined speed.

- 5 4. In speed equalizing devices for phonographs, the combination with a revoluble turntable, a shaft on the upper end of which said turntable is mounted, and a spiral spring the inner end of which is permanently secured to said shaft, of an annular member surrounding said spring concentric to said shaft and adapted to frictionally engage the outer convolution of said spring, and mechanism for revolving said annular member.

- 10 5. In speed equalizing devices for phonographs, the combination with a revoluble turntable, a shaft on the upper end of which said turntable is mounted, and a spiral spring the inner end of which is permanently secured to said shaft, a casing surrounding said spring concentric to said shaft and having an inner annular surface and adapted to be frictionally engaged by the outer convolution of said spring, and mechanism for revolving said annular member.

- 20 6. In speed equalizing devices for phonographs, the combination with a revoluble turntable, a shaft on the upper end of which said turntable is mounted, and a spiral spring the inner end of which is permanently secured to said shaft, of an annular casing surrounding said spring concentric to said shaft, an annulus in the interior of said casing adapted to be frictionally engaged by the outer convolution of said spring, and mechanism for revolving said annular member.

- 25 7. In speed equalizing devices for phonographs, the combination with a revoluble turntable, a shaft on the upper end of which said turntable is mounted, and a spiral spring the inner end of which is perma-

nently secured to said shaft, of an annular casing surrounding said spring concentric to said shaft, and having an inner annular surface and adapted to be frictionally engaged by the outer convolution of said spring, a gear connected to said casing, a motor, and gearing transmitting motion from said motor to said first mentioned gear.

8. In speed equalizing devices for phonographs, the combination with a revoluble turntable, a shaft on the upper end of which said turntable is mounted, and a spiral spring the inner end of which is permanently secured to said shaft, of an annular member surrounding said spring concentric to said shaft and adapted to engage the outer convolution of said spring, mechanism for revolving said annular member, a gear securely mounted on said shaft, and governor mechanism driven thereby.

9. In speed equalizing devices for phonographs, the combination with a revoluble turntable, a shaft on the upper end of which said turntable is mounted, and a spiral spring the inner end of which is permanently secured to said shaft, of an annular casing surrounding said spring concentric to said shaft and having an inner annular surface adapted to be frictionally engaged by the outer convolution of said spring, a gear connected to said casing, a motor and gearing for transmitting motion from said motor to said first mentioned gear, a gear securely mounted on said shaft, and governor mechanism driven thereby.

In witness whereof I have hereunto set my hand this 23rd day of April, 1918.

CLIFFORD H. GREEN.
